BURNER CONTROL SYSTEM

Daniel G. Taylor, Minneapolis, and Willis H. Gillie, St. Paul, Minn., assignors to Minneapolis-Honeywell Regulator Company, Minneapolis, Minn., a corporation of Delaware

Application August 20, 1942, Serial No. 455,428

10 Claims. (Cl. 158—28)

This invention is directed broadly to an automatic control system for fluid fuel burners and is more particularly directed to a system which does not rely upon a thermal element responsive to combustion conditions for timing the trial ignition period and time required for the system to recycle, but provides a separate timing means for accomplishing these functions.

It is old in prior art systems to utilize a timing means such as a thermal timer for timing recycle and trial ignition periods but these systems in the past have been very complicated and cumbersome and usually require more than one relay to accomplish the necessary timing functions and to provide the required features of safety. One of the main objects of the present invention is to provide a relatively simple system of the above type which requires only one relay, one thermal timer, and the usual safety switch.

A further object of the invention is to provide a system of the above type which may be used in combination with a very sensitive and rapidly operating combustion responsive device for indicating whether combustion is present or absent at the burner, and in which the hot and cold switches of the combustion responsive device need not overlap in their operation in either direction.

A further object of the invention is to provide a control system of the above type in which a single relay closes a maintaining circuit for itself which is independent of the combustion responsive device while the combustion responsive device opens a cold switch and closes a hot switch, and in which a thermal timer responsive to the closure of the hot switch opens the maintaining circuit so that in running condition the relay will be held in through the hot combustion responsive switch. This invention further contemplates that the thermal timer may be utilized for terminating ignition a predetermined time after the hot switch has been closed and may also operate a switch in the initial energizing circuit for the relay so that the relay may not be energized until a predetermined time has elapsed from the previous burner operation and deenergization of the heater for the thermal timer.

An additional feature of the invention is that the safety switch heater is maintained in operation during the time that the maintaining circuit for the relay is closed so that the safety switch is operative to shut the system down and lock it out in the event that the cold combustion

switch remains closed due to a failure of the fuel to properly ignite.

A further object of the invention is to accomplish the above results by means of a latch operated by the thermal timer so that the relay when energized will close the switch to the maintaining circuit and the thermal timer when heated will rotate the latch and permit an arm to open the maintaining switch and also open the ignition switch.

It is further contemplated that where this system is powered from the low voltage secondary winding of a step-down transformer, the maintaining circuit which keeps the relay energized while the combustion responsive device is opening the cold switch and closing the hot switch, will be connected to a tap in the secondary winding so that the safety switch heater will remain energized as long as the cold combustion switch is closed for locking the system out in the event that combustion is not established.

These and other objects will readily become apparent as the following specification is read in the light of the accompanying drawing, in which:

Figure 1 is a schematic diagram of a control system for a fuel burner which incorporates the various features of our invention.

Figure 2 is a side elevation of the relay, thermal timer and latching mechanism, with a side cover removed to show substantially all of the elements in elevation, and

Figure 3 is a detail view of a modified form of our invention.

Referring first to Figure 2 of the drawing, the reference numeral 10 indicates an insulating casing in which the side cover has been removed. Within the casing 10 is a bimetallic blade 11 having a relatively fixed end 12 which is pivotally mounted to a fixed portion of the casing by means of a disc element 13 of a slip friction connection, element 13 being shown in elevation. The disc element 13 is rotatably mounted about a pin 14 shown in section. The element 13 is urged by a coil spring shown in section at 15 into engagement with a friction element (not shown) interposed between disc 13 and a stationary surface in the rear of disc 13. On the free end 16 of the bimetallic blade 11 is a movable contact 17 which is adapted to cooperate with a stationary contact 18 carried upon the resilient contact blade 19 which is biased downwardly into engagement with a cam 20 which is eccentrically mounted with respect to an adjustment screw 21. The screw 21 is suitably mounted in the casing

50 which is adapted to cooperate with a stationary contact 18 carried upon the resilient contact blade 19 which is biased downwardly into engagement with a cam 20 which is eccentrically mounted with respect to an adjustment screw 21. The screw 21 is suitably mounted in the casing

10 so that upon rotation of the screw the stationary contact 18 may be adjusted vertically with respect to the movable contact 17.

An electric heating element 23 is carried in the casing adjacent the bimetallic blade 11 by means of the two brackets 24. The heater is insulated by means of the two mica sheets shown at 25. A bracket, a portion of which is shown at 27, pivotally carries a latch member 28 which in turn carries a resilient latch blade 29, the free end being adjustable with respect to the latch member 28 by means of the adjusting screw 30. An extension 31 on the latch member 28 adjustably carries a screw 32, the head of which is adapted to be engaged by the free end 16 of the bimetallic blade 11 for rotating the latch 28 about its pivot 33 on the bracket 27.

A resilient contact blade 35 is suitably fixed at one end to the bracket 36 and at its free end carries a contact 37. The blade 35 carries an insulating arm 38 and forms the hinged support for this arm biasing it for movement in a downwardly direction.

The reference numeral 40 indicates the pivoted armature of an electromagnetic relay of the type shown in Patent 2,241,838, which issued May 13, 1941, to J. M. Wilson. The coil and core of this relay cannot be seen in Figure 2 because they are located directly behind the casing 10. The armature 40 is provided with a biasing spring (not shown) which biases the armature to its upper or unattracted position, in which it is shown in Figure 2. This spring is also invisible in this figure because it is located behind the casing 10. The armature 40 is provided with an extension 41 which extends beneath the arm 38 and raises this arm to the position shown in Figure 2 when the armature 40 is in its unattracted position. The armature 40 carries a second projection 42 which has a conducting segment 43 which electrically bridges the contact 37 and a second contact located directly behind it. With the armature in the position shown in Figure 2, the electrical circuit is broken between these two contacts but when the relay is energized the conducting segment 43 electrically connects the contacts. A coil spring 45 is located between the projection 41 on the armature 40 and the latch member 28 and biases the latch member for rotation in a clockwise direction to its operative position. A contact bracket 47 is fixedly mounted in the casing 10 and carries an adjustable contact screw 48. The casing 10 also supports a resilient contact blade 49 having a movable contact 50. The contact blade 49 extends upwardly beyond the contact 50 and cooperates with an extension 51 on the arm 38. It will be noted that with the parts in the position shown in Figure 2 there is a slight space between the extension 51 and the resilient contact blade 49. The purpose for this will appear later.

When the armature 40 moves to its attracted position the extension 41 thereof will permit the arm 38 to move downwardly as a result of the bias placed thereon by the resilient blade 35. This will cause the latching surface 53 to engage the free end of the resilient latching blade 29 which prevents further movement of the arm 38 at this time. This movement of the arm 38 causes the extension 51 to take up the space between the extension and the resilient blade 49 but the contact 50 will remain in engagement with the stationary contact 48 as long as the arm 38 is latched upon the free end of the latching member 29. If the electric heating element 23 is en-

ergized at this time it will heat the bimetallic blade 11 and cause the free end 16 to warp in an upwardly direction and therefore start to rotate the latching member 28 in a counterclockwise direction. After a predetermined period of time the latching member 28 will have rotated far enough to move the latching blade 29 from beneath the latching surface 53 and thus permit the arm 38 to drop down further until it again engages the extension 41 on the armature 40. This movement of the arm 38 will cause the extension 51 to move contact 50 out of engagement with the contact 48 and will also move the contact 37 out of engagement with the bridging member 43 on the armature 40. The bimetallic blade 11 will continue to rotate the latching member 28 until it engages the fixed stop 54, which will prevent further rotation thereof. If the temperature of the bimetallic blade 11 is still increasing at this time it will continue to warp and such additional warping movement will be accommodated by means of the slip friction connection 13 which will permit an upward movement of the end 12 of the bimetallic blade 11.

It will be noted also that as the free end 16 of bimetallic blade 11 warps in an upwardly direction that the contacts 17 and 18 are separated. Upon deenergization of the relay, the armature 40 will return to its unattracted position as shown in Figure 2 at which time the extension 41 thereon will raise the arm 38 and return it to the position shown in which it will again permit the resilient contact blade 49 to move the contact 50 back into engagement with the stationary contact 48. If the electric heating element 23 is deenergized at this time, the bimetallic blade 11 will commence to warp in the opposite direction which will cause a lowering of the free end 16 and will eventually cause the contact 17 to reengage the stationary contact 18. As the end 16 of the bimetallic blade 11 moves downwardly, it permits the biasing spring 45 to return the latch member 28 to the position shown in Figure 2 in which it will again latch the arm 38 when the armature 40 moves to its attracted position. Downward movement of the free end 16 of the bimetallic blade 11 will be limited by the engagement of the two contacts 17 and 18 and if the blade 11 continues to cool after this engagement takes place it will continue to warp due to the slip friction connection including disc element 13. By providing this slip friction connection, the timing function of the latch 28 is facilitated due to the fact that it is not necessary to wait until the bimetallic blade heats up to its final temperature or cools to its final temperature before it performs its desired function. It will be understood of course, that the time required for the bimetallic blade 11 to cause the latch 28 to release the arm 38 may be adjusted by means of the two adjustable screws 30 and 32. Also, the time required for the bimetallic blade 11 to reclose the contacts 17 and 18 following a deenergization of the electric heater 23 may be adjusted by rotating the screw 21 and eccentric 20 which vertically positions the contact 18 with respect to the movable contact 17.

All of the elements of Figure 2, with the exception of shaft 14, spring 15, and shaft 21 are shown in elevation in Figure 2, as will be apparent from the above description.

Referring now to the schematic diagram of the whole system shown in Figure 1, it will be noted that the parts which are common to Figures 1 and 2 have been given the same reference numer-

als in Figure 1 as they have in Figure 2. It will be understood that the armature 40 of the relay is adapted to actuate other switches than the one formed by the contact 37 and bridging member 43. These additional switches have been indicated schematically by the pivoted relay arms 55, 56, and 57 which engage the stationary contacts 58, 59 and 60, respectively, when the armature is in its attracted position and are in open circuit position when the armature 40 is in its unattracted position. The above switches are located in a low voltage circuit whereas the relay arm 61 is adapted to engage stationary contact 62 in the high voltage circuit when the armature 40 is in its attracted position and the arm 61 is moved to open circuit position when the armature 40 is in its unattracted position. The relay coil for attracting the armature 40 has been indicated by the reference numeral 63 and dotted lines indicate the armature 40 diagrammatically.

This system is provided with the usual safety switch which includes a pair of contact blades 65 and 66 which are biased to open contact position but which are latched closed by the free end of a bimetallic blade 67. This blade is adapted to be heated by the electric heater 68 and when so heated will warp to the left and release the contact blade 66 for movement to open circuit position. The safety switch will then be locked in open position and will have to be reset by means of the manual reset button 69, which is of the trip free reset type, that is, it maintains the switch in open circuit position during the resetting operation so that the switch cannot be closed unless the bimetallic blade 67 has cooled to a point where it will relatch the switch upon release of the button 69.

This control system may obviously be placed under the control of many different types of condition responsive devices, but for the purposes of illustration it has been shown as being under the control of a thermostat which takes the form of a bimetallic blade 71 which is fixed at one end and which carries at its free end a pair of contact blades 72 and 73 which cooperate respectively with the two stationary contacts 74 and 75. These contacts are so arranged that on a decrease in temperature at the thermostat 71 it will contract and first cause the resilient contact blade 73 to engage the stationary contact 75 and then at a slightly lower temperature cause the contact blade 72 to engage the stationary contact 74.

This system is further provided with a combustion responsive device 77 which is shown as comprising a movable switch arm 78 which cooperates respectively with a cold contact 79 and a hot contact 80. This device is preferably not calibrated but is so arranged that the cold contact is closed in the absence of combustion and the hot contact is closed in the presence of combustion.

The reference numeral 83 indicates an electric motor or an electrically operated valve for controlling the flow of fuel to a burner. Although it will be readily appreciated that various types of fuel may be controlled with this system, for the purposes of illustration, it may be assumed that the reference numeral 83 indicates the usual oil burner motor and 84 the usual spark ignition for igniting the oil delivered to the burner. A step-down transformer is shown at 85 which comprises a primary winding 86 and a secondary winding 87. The primary winding 86 is con-

nected to the supply lines 88 and 89 by means of the two conductors 90 and 91.

Operation

5 The various elements are shown in Figure 1 in the position which they will occupy when the thermostat 71 is satisfied and has therefore moved the two contact blades 72 and 73 to their open circuit position. In such case the relay winding 63 will be deenergized and therefore the armature 40 will be in its unattracted position and the switch arms 55, 56, 57, and 61 will be in open circuit position. The bimetallic timing blade 67 is cold and has closed the contacts 17 and 18. 10 There is no combustion present at the burner due to the fact that the burner motor 83 and ignition device 84 are deenergized by the relay 61 which is in open circuit position. The combustion responsive device 77 has therefore moved the switch arm 78 into engagement with the cold contact 79. 15

Under such conditions the temperature at the thermostat 71 will begin to decrease and cause this thermostat to move the resilient contact blade 73 into engagement with its stationary contact 75. No circuit will be established at this time due to the fact that the switch blade 72 and the switch arm 61 are both in open circuit position. The temperature at the thermostat 71 will therefore continue to decrease until the switch blade 72 is moved into engagement with the stationary contact 74. This establishes an energizing circuit for the relay winding 63 which extends from one side of the secondary winding 87 through conductor 93, relay winding 63, conductor 94, safety switch blades 65 and 66, conductor 95, contact 75, switch blades 73 and 72, contact 74, conductors 96 and 97, bimetallic blade 67, contacts 17 and 18, conductor 98, safety switch heater 68, conductor 99, cold contact 79, switch arm 78, and conductor 100 back to the other side of the secondary winding 87. Energization of the relay winding 63 results in the movement of the armature 40 to its attracted position and the movement of the switch arms 55, 56, 57, and 61 into engagement with their stationary contacts 58, 59, 60 and 62. At the same time the armature 40 causes the movement of the bridging element 43 into engagement with the contact 37 as the armature rotates about its pivot 39. 30

The attraction of the armature 40 sets up a holding circuit for the relay winding 63 which is independent of the switch blade 72 and contact 74. This circuit extends from one side of the secondary winding 87 through conductor 93, relay winding 63, conductor 94, safety switch blades 65 and 66, conductor 95, contact 75, switch blade 73, bimetallic element 71, conductor 101, contact 60, relay arm 57, conductor 102, relay arm 56, contact 59, conductors 103 and 97, bimetallic blade 67, contacts 17 and 18, conductor 98, safety switch heater 68, conductor 99, cold contact 79, switch arm 78, and conductor 100 back to the other side of the secondary winding 87. 45

60 At the same time a parallel circuit for the relay winding 63 is set up. This circuit extends from one side of the secondary winding 87 through conductor 93, relay winding 63, conductor 94, safety switch blades 65 and 66, conductor 95, contact 75, switch blade 73, bimetallic element 71, conductor 101, contact 60, relay arm 57, conductors 102 and 105, relay arm 55, contact 58, conductors 106 and 107, switch blades 47 and 49, and conductor 108 to a tap 109 in the second-

ary winding 87. It will be noted that the last traced circuit for the relay winding 63 did not pass through the combustion responsive device 77. Thus, the relay winding 63 will remain energized while the combustion responsive switch arm 78 leaves the cold contact 79 and later establishes contact with the hot contact 80. The safety switch heater 66 remains energized all this time, however, so that if combustion should not be established and the switch arm 78 should remain in engagement with the cold contact 79, the blade 61 of the safety switch will be heated and will release the safety switch for movement to open position. This will, of course, shut the system down and lock it out until it is manually reset by the manual reset button 69.

It will be realized of course that the relay winding 63 upon being energized also causes the relay arm 61 to engage the stationary contact 62. This establishes a circuit for the burner motor 83 which extends from one line wire 88 through conductor 110, burner motor 83, conductors 111 and 112, stationary contact 62, relay arm 61, and conductor 113 to the other line wire 89. The ignition device 84 is simultaneously energized through a circuit extending from the line wire 88 through conductor 114, ignition device 84, conductor 115, switch blade 35, contact 37, bridging member 43, conductors 116 and 112, contact 62, relay arm 61, and conductor 113 back to the line wire 89.

Normally the energization of the burner motor and ignition device will cause the establishment of combustion at the burner and the combustion responsive device 77 will cause the switch arm 78 to leave the cold contact 79 and engage the hot contact 80. It has been pointed out above that the relay winding 63 will remain energized during this operation. Engagement of the switch arm 78 with the hot contact 80 will establish a holding circuit for the relay winding 63 which extends from one side of the secondary winding 87 through conductor 93, relay winding 63, conductor 94, safety switch blades 65 and 66, conductor 95, contact 75, switch blade 73, bimetallic element 71, conductor 101, contact 60, relay arm 57, conductors 102 and 105, relay arm 56, stationary contact 58, conductors 106 and 117, electric heating element 23, conductor 118, hot contact 80, switch arm 78 and conductor 100 back to the other side of the secondary winding 87. It will be noted that this circuit extends through the electric heating element 23 for the bimetallic timer 11. An additional circuit for this heating element extends from the tap 109 of the secondary winding 71, through conductor 108, contact blades 49 and 47, conductors 107 and 117, electric heating element 23, conductor 118, hot contact 80, switch arm 78, and conductor 100 back to the other side of the secondary winding 87.

This results in the heating of the bimetallic element 11 which causes it to warp in a direction to rotate the latch 28 in counter-clockwise direction and after a predetermined period of time this latch will release the arm 38 which will move contact 37 to open circuit position and also move contact blade 49 to open circuit position. The movement of the contact 37 to open circuit position will deenergize the circuit to the ignition device 84 and therefore terminate ignition. The moving of the contact blade 49 to open circuit position will interrupt the maintaining circuit for the relay winding 63 with the result that this relay winding is now energized by a circuit which extends through the safety switch 65, 66, bimetal-

lic thermostat switch 73, 75 and the hot combustion responsive switch 80, 78. This is the running condition of the circuit.

If a flame failure should occur, the combustion responsive switch arm 78 will disengage the hot contact 80 thereby deenergizing the relay coil 63 and returning the armature 40 to its unattracted position. The circuit through the relay winding 63 cannot be reestablished for starting the system in operation until the bimetallic element 11 has cooled sufficiently to cause engagement of the contacts 17 and 18. The same will be true if the relay winding 63 were deenergized by the thermostat 11 becoming satisfied. Thus the time required for the bimetallic element 11 to cool determines the time necessary for the system to recycle and the time required for this element to heat determines the time the ignition device shall be energized following the initial establishment of combustion. The trial ignition period is determined as usual by the timing of the safety switch 65, 66.

Figure 3 discloses a modified form of our invention in which an electromagnet is utilized for releasing the arm 38 to open circuit position. Specifically the latching surface 53 cooperates with the latch 130 when the armature 40 is in its attracted position. Latch 130 is pivoted at 131 and is biased to its latching position by the biasing spring 132. At such time the contact 17 carried by the latch 130 is in engagement with its stationary contact 18.

The latch 130 is made of magnetic material and an electromagnet 134 is located adjacent thereto. When combustion has been established, as explained in connection with the operation of Figure 1, the winding 135 for the electromagnet is energized and the electromagnet attracts the latch 130, which pivots to the left, separating the contacts 17 and 18 and releasing the arm 38 for movement to open circuit position as in Figure 1. It will be noted that the winding 135 is connected between the conductors 117 and 118 in place of the electric heater 23 of Figure 1.

The system utilizing the modification of Figure 3 would function the same as Figure 1 except that the ignition would terminate as soon as combustion was established and there would be no timer for timing the scavenger period. In other words the starting contacts 17, 18 would be closed as soon as armature 40 dropped out and the recycle would be timed entirely by the cold combustion switch.

Many changes and modifications in this invention will doubtless occur to those who are skilled in the art and we therefore wish to point out that we intend to be limited only by the scope of the appended claims and not by the specific embodiment of the invention which has been disclosed herein merely for the purpose of illustration.

We claim as our invention:

1. Fluid fuel burner control apparatus comprising in combination, means including an electromagnetic relay adapted to control the flow of fuel to a burner, hot and cold switches, a combustion responsive device adapted to close said cold switch in the absence of combustion and to close said hot switch in the presence of combustion, a main switch, a circuit for energizing said main switch and cold switch, a maintaining switch closed by said relay, a further switch, a circuit for maintaining energization of said relay while said combustion responsive device opens said cold switch and

closes said hot switch, said maintaining circuit including said main switch, further switch, and maintaining switch, a thermal timer, a heater therefor, a holding circuit for said relay including in series said relay, main switch, thermal timer heater and hot switch, and means operated by said thermal timer for opening said further switch a substantial time after the closure of said holding circuit.

2. Fluid fuel burner control apparatus comprising in combination, an electrical device adapted to control the flow of fuel to a burner, hot and cold switches, a combustion responsive device adapted to close said cold switch in the absence of combustion and to close said hot switch in the presence of combustion, a main switch, a source of power including a transformer winding, an energizing circuit for said electrical device connected across said transformer winding, said circuit including said main switch and cold switch, a maintaining switch closed as a result of the closure of said energizing circuit, a circuit for maintaining energization of said electrical device while said combustion responsive device opens said cold switch and closes said hot switch, said maintaining circuit extending from one side of said transformer winding to an intermediate portion thereof and including said main switch and said maintaining switch, a holding circuit for said electrical device connected across said transformer winding and including said main switch and hot switch, and means for opening said maintaining circuit after the closure of said holding circuit.

3. Fluid fuel burner control apparatus comprising in combination, an electrical device adapted to control the flow of fuel to a burner, hot and cold switches, a combustion responsive device adapted to close said cold switch in the absence of combustion and to close said hot switch in the presence of combustion, a safety switch in control of said electrical device, a thermal actuator for said safety switch, a heater for said thermal actuator, a main switch, a source of power including a transformer winding, an energizing circuit connected across said transformer winding, said circuit including said main switch, heater for said thermal actuator and cold switch, a maintaining switch closed as a result of the closure of said energizing circuit, a further switch, a circuit for maintaining the energization of said electrical device while said combustion responsive device opens said cold switch and closes said hot switch, said maintaining circuit being connected from one side of said transformer winding to an intermediate portion thereof and including said further switch, main switch and maintaining switch, a holding circuit for said electrical device, said holding circuit including said main switch and hot switch, and means for opening said further switch following the closure of said hot switch.

4. In a system for controlling a fluid fuel burner and ignition means therefor; an electrical device adapted to control the delivery of fuel to said burner, said device comprising an electromagnetic relay having a movably mounted armature biased to its unattracted position and adapted when moved to its attracted position to cause energization of said burner, a rotatably mounted latch biased to its operative position, an arm biased for movement into engagement with said latch but held out of engagement therewith by said armature in its unattracted position, a first switch closed by said armature as it is pulled in

5 by said relay upon energization thereof, said armature also providing for movement of said arm into engagement with said latch, a thermal element, an electric heater for heating said thermal element, means operated by said thermal element upon heating thereof for rotating said latch in a direction to release said arm to its tripped position, thereby opening said first switch and means operated by said armature upon deenergization of said relay for moving said arm out of engagement with said latch to permit said latch to return to its operative position under the influence of its bias; circuit connections adapted to be connected to a main switch and a starting switch and to be effective when so connected to establish an energizing circuit for said relay including said main switch and starting switch; circuit connections adapted to be connected to an ignition means and when so connected to form an energizing circuit for said ignition means including said first switch; and circuit means adapted to be connected to a device responsive to combustion and to said main switch and effective to establish a holding circuit for said relay independent of said starting switch and including said main switch and electric heater.

5. In a system for controlling a fluid fuel burner; in combination, a fluid fuel burner; an ignition means therefor; an electrical device for controlling the delivery of fuel to said burner, said device comprising an electromagnetic relay having a movably mounted armature biased to its unattracted position and effective when moved to its attracted position to cause energization of said burner, a rotatably mounted latch biased to its operative position, an arm biased for movement into engagement with said latch but held out of engagement therewith by said armature in its unattracted position, a first switch closed by 10 said armature as it is pulled in by said relay upon energization thereof, said armature also providing for movement of said arm into engagement with said latch, a thermal element, an electric heater for heating said thermal element, means operated by said thermal element upon heating thereof for rotating said latch in a direction to release said arm to its tripped position, thereby opening said first switch, means operated by said armature upon deenergization of said relay for moving said arm out of engagement with said latch to permit said latch to return to its operative position under the influence of its bias, and a second switch opened by said arm as it moves to its tripped position and closed by said arm as 15 said armature returns to its unattracted position; a main switch; a combustion responsive device including hot and cold switches and operative to close said cold switch in the absence of combustion and to close said hot switch in the presence of combustion; an energizing circuit for said relay including said main switch and cold switch; an energizing circuit for said ignition means including said first switch; a maintaining circuit for said relay independent of both said hot and cold switches and including said main switch and said second switch; and a holding circuit for said relay including said main switch, said hot switch, and said electric heater.

6. In a system for controlling a fluid fuel burner, in combination, a fluid fuel burner; an ignition means therefor; an electrical device for controlling the delivery of fuel to said burner, said device comprising an electro-magnetic relay having a movably mounted armature biased to its unattracted position and effective when moved

to its attracted position to cause energization of said burner, a rotatably mounted latch biased to its operative position, an arm biased for movement into engagement with said latch but held out of engagement therewith by said armature in its unattracted position, a first switch closed by said armature as it is pulled in by said relay upon energization thereof, said armature also providing for movement of said arm into engagement with said latch, a bimetallic blade, a fixed support, slip friction means for mounting said blade at one end to said fixed support, an electric heater for heating said bimetallic blade, means operated by the other end of said blade upon heating for rotating said latch in a direction to release said arm to its tripped position, thereby opening said first switch, means limiting the movement of said other end of said blade in each direction, said slip friction means accommodating further warping of said blade, and means operated by said armature upon deenergization of said relay for moving said arm out of engagement with said latch to permit said latch to return to its operative position under the influence of its bias, and a second switch opened by said arm as it moves to tripped position and closed by said arm as said armature returns to its unattracted position; a main switch: a combustion responsive device including hot and cold switches and operative to close said cold switch in the absence of combustion and to close said hot switch in the presence of combustion; an energizing circuit for said relay including said main switch and cold switch; an energizing circuit for said ignition means including said first switch; a maintaining circuit for said relay independent of both said hot and cold switches and including said main switch and said second switch; and a holding circuit for said relay including said main switch, said hot switch, and said electric heater.

7. In a system for controlling a fluid fuel burner, in combination, a fluid fuel burner; an ignition means therefor; an electrical device for controlling the delivery of fuel to said burner, said device comprising an electro-magnetic relay having a movably mounted armature biased to its unattracted position and effective when moved to its attracted position to cause energization of said burner, a rotatably mounted latch biased to its operative position, an arm biased for movement into engagement with said latch but held out of engagement therewith by said armature in its unattracted position, a first switch closed by said armature as it is pulled in by said relay upon energization thereof, said armature also providing for movement of said arm into engagement with said latch, a thermal element, an electric heater for heating said thermal element, means operated by said thermal element upon heating thereof for rotating said latch in a direction to release said arm to its tripped position, thereby opening said first switch, means operated by said armature upon deenergization of said relay for moving said arm out of engagement with said latch to permit said latch to return to its operative position under the influence of its bias, and switch means closed by said thermal element when it is in its cold position and opened when it is in all other positions; means under the control of said last named switch means for effecting energization of said relay; means including a device responsive to combustion for establishing a holding circuit to said relay independent of said last named switch means and including said elec-

tric heater; and means including said first switch for establishing a circuit to said ignition means.

8. In a system for controlling a fluid fuel burner, in combination, a fluid fuel burner; an ignition means therefor; an electrical device for controlling the delivery of fuel to said burner, said device comprising an electromagnetic relay having a movably mounted armature biased to its unattracted position and effective when moved to its attracted position to cause energization of said burner, a rotatably mounted latch biased to its operative position, an arm biased for movement into engagement with said latch but held out of engagement therewith by said armature in its unattracted position, a first switch closed by said armature as it is pulled in by said relay upon energization thereof, said armature also providing for movement of said arm into engagement with said latch, a bimetallic blade, a fixed support, slip friction means for mounting said blade at one end to said fixed support, an electric heater for heating said bimetallic blade, means operated by the other end of said blade upon heating for rotating said latch in a direction to release said arm to its tripped position thereby opening said first switch, means limiting the movement of said other end of said blade in each direction, said slip friction means accommodating further warping of said blade, means operated by said armature upon deenergization of said relay for moving said arm out of engagement with said latch to permit said latch to return to its operative position under the influence of its bias, a cold contact engaged by said other end of said blade when it is in its cold position, and means adjusting the position of said cold contact for varying the time required for said blade to engage said contact following the deenergization of the heater for said blade; means under the control of said cold contact for effecting energization of said relay; means including a device responsive to combustion for establishing a holding circuit to said relay independent of said cold contact and including said electric heater; and means including said first switch for establishing a circuit to said ignition means.

9. Fluid fuel burner control apparatus comprising in combination, an electrical device adapted to control the flow of fuel to a burner, an electrical ignition device, hot and cold switches, a combustion responsive device adapted to close said cold switch in the absence of combustion and to close said hot switch in the presence of combustion, a main switch, a source of power including a transformer winding, an energizing circuit for said electrical device connected across said transformer winding, said circuit including said main switch and cold switch, a maintaining switch closed as a result of the closure of said energizing circuit, a circuit for maintaining energization of said electrical device while said combustion responsive device opens said cold switch and closes said hot switch, said maintaining circuit extending from one side of said transformer winding to an intermediate portion thereof and including said main switch and said maintaining switch, a holding circuit for said electrical device connected across said transformer winding and including said main switch and hot switch, a circuit to said ignition device controlled by said electrical device, and means for opening said ignition circuit and said maintaining circuit a predetermined time after the closure of said holding circuit.

10. Fluid fuel burner control apparatus com-

prising in combination, an electrical device adapted to control the flow of fuel to a burner, an electrical ignition device, hot and cold switches, a combustion responsive device adapted to close said cold switch in the absence of combustion and to close said hot switch in the presence of combustion, a main switch, time switch means, a thermal actuator therefor including an electrical heater and operable when the electric heater is energized to cause said time switch means to assume an open circuit position a predetermined period of time after energization of said heater, a source of power including a transformer winding, an energizing circuit for said electrical device connected across said transformer winding, said circuit including said main switch and cold switch, a maintaining switch closed as a result of the closure of said energizing circuit, a circuit for maintaining energization of said elec-

trical device while said combustion responsive device opens said cold switch and closes said hot switch, said maintaining circuit extending from one side of said transformer winding to an intermediate portion thereof and including said main switch, time switch means and maintaining switch, a holding circuit for said electrical device connected across said transformer winding and including said main switch, hot switch, and electrical heater, and a circuit for said ignition device controlled by said electrical device and by said time switch means, said time switch means being operable a predetermined period of time after energization of said holding circuit to interrupt said maintaining circuit and the circuit to said ignition device.
